SPOOL

Hilyard C. Howsam, Chicago, Ill., assignor to
 Hubbard Spool Company, Chicago, Ill., a corporation of Illinois

Application October 6, 1941, Serial No. 413,757

8 Claims. (Cl. 242—123)

My invention relates to spools constructed entirely of sheet metal and adapted particularly for supporting wire. The important object of the invention is to produce a spool which can be economically manufactured, and which is comparatively light but of rugged construction resistant to service strains and abuse.

The various features of construction and arrangement involved in the spool will become apparent from the drawing and the specification.

On the drawing:

Figure 1 is an end view of a spool;

Figure 2 is a section on plane II—II of Fig. 1; and

Figure 3 is a section on plane III—III of Fig. 2.

The barrel B of the spool comprises similar halves drawn from sheet metal and each comprising a circular wall 10 and a flange part 11 extending radially from the outer end of the wall 10. The circular body portions 10 abut at their inner ends and are rigidly secured together by a circular tie plate 12 welded thereto as indicated at 13.

The heads H for the spool are in the form of circular sheet metal disks. The outer peripheral portion 14 of each head rests against the corresponding flange 11 and the outer portion of each flange is deflected outwardly into substantially semi-circular cross section to snugly receive and engage around the edge of the peripheral portion 14 of the head. The central portion 15 of each head is deflected outwardly with its outer surface terminating in or short of the plane of the outer surface of the deflected outer end of the corresponding barrel flange 11. The intermediate portion 16 of each head is deflected inwardly to provide a shoulder 17 abutting the corner between the corresponding flange 11 and body portion 10 of the spool, this annular shoulder 17 then serving to hold the barrel end to true circular form.

Within the barrel at each end thereof is a brace or truss member T of sheet metal. Each truss is of U-shaped cross section and extends diametrically the full width of the barrel below the corresponding head H with its bottom or yoke wall 18 engaging against the intermediate portion 16 of the head and rigidly secured thereto, preferably by spot welding as indicated at 19.

The flanges 20 of each brace structure T have their center portions deflected laterally outwardly to provide opposed circular arc portions 21 forming sockets, and between these portions the yoke of the brace member is extruded outwardly to provide an annular flange 22 concentric with the

portions 21. The flange 22 of each brace member extends into the inner annular portion 15 of the corresponding head concentric therewith and the portion 15 is extruded and deflected to form an inwardly extending annular flange 23 telescoping the flange 22 of the brace member and to provide the axial passageway 24. Each brace member T by being welded to the head and radially interlocked with the central portion 15 of the head thus materially strengthens and stiffens the head against axial distortion under heavy service. The brace members at opposite ends of the barrel may extend parallel or may extend in different diameters as shown on Figs. 2 and 3.

An arbor or core tube A is provided in alignment with the passageways 24 in the heads for receiving arbors or other supports for the spool when the spool is being wound or unwound. This arbor tube may be a length of sheet metal tubing or may be formed from a blank of sheet metal. At its ends the arbor tube fits snugly in the sockets formed by the opposed arcuate portions 21 of the respective brace members T to be secured thereto as by spot welding as indicated at 25. The arbor tube is provided near each end with an annular external bead or shoulder 26 for abutting against the inner ends of the arcuate portions 21 of the respective brace members T which receive the ends of the tube. The arbor tube thus forms a strut between the brace members to which it is welded so that these brace members will be held intimately against the respective spool heads which are thus strengthened against axial displacement under service or loads.

In order that the various spool parts may be accurately assembled, the barrel portions 10 are provided with longitudinally extending indentations 27 forming aligning keys 28 on the inner side. The two barrel halves are assembled with these keys in alignment and the tie plate 12 is provided with an indentation 29 to receive the keys, as shown on Fig. 2. The heads H are provided with indentations 30 which receive the outer ends of the keys for proper location of the heads relative to the barrel.

In order to connect the spool with a driving pin when the spool is to be wound or unwound, the inner portions 15 of the spool heads are provided with openings 31. As shown on Fig. 3 these openings may be surrounded by inner flanges 32 for adequate engaging surface with a driving pin.

I thus produce a spool constructed of comparatively light sheet metal but amply braced and trussed to withstand strains and to prevent

distortion under heavy service and use. I have shown a practical and efficient embodiment of the features of my invention but I do not desire to be limited to the exact construction and arrangement shown and described as changes are possible without departing from the scope of the invention.

I claim as follows:

1. A spool comprising a sheet metal barrel having radial flanges at its ends, heads engaging along their outer peripheral portions with the respective flanges, an intermediate annular portion of each head being deflected inwardly, a cross brace extending diametrically within each end of said barrel and welded to the corresponding head intermediate portion, and interengaging flanges on each head and the corresponding brace member.

2. A sheet metal spool comprising a barrel having flanges at its ends, heads for said barrel having their outer peripheral portions seating against the respective flanges, an intermediate annular portion of each head being deflected inwardly to provide an annular shoulder behind the respective barrel flange, a transversely extending brace member in each end of said barrel spot welded to the deflected intermediate portion of the corresponding head, each head having an axial passageway surrounded by an inwardly extending flange, and an outwardly extending flange on each brace member receiving the inwardly extending flange of the respective head.

3. A sheet metal spool comprising a barrel having flanges at its ends, heads for said barrel engaging against the outer sides of said flanges, a brace member extending diametrically across the barrel within each end thereof and welded to the respective head, the central portion of each head being deflected outwardly and being provided with an axial passageway therethrough, a flange extending inwardly around said passageway, and an outwardly extending flange on each brace member concentric with and telescoping the inwardly extending flange on the respective head.

4. A sheet metal spool comprising a barrel with flanges at its ends, heads for said barrel engaging with and secured against the outer sides of said flanges, a brace member extending across the barrel within each end thereof and being of U-shape cross section to provide a back wall and inwardly extending flanges, the back walls of said brace members being welded against the inner side of the respective heads, an arbor tube having its ends extending between the flanges of the respective brace members and rigidly secured thereto, and passageways in said heads in alignment with said arbor tube.

5. A sheet metal spool comprising a barrel hav-

ing flanges at its ends, heads for said barrel secured against the outer sides of said flanges, a brace member extending diametrically across the barrel within each end thereof and being of U-

5 shaped cross section to provide a back wall and flanges, the back wall of each brace member being welded to the inner side of the respective head and the brace member flanges extending inwardly, an arbor tube having its ends extending 10 between the flanges of the brace members and rigidly secured thereto, shoulders on said arbor tube abutting the inner edges of the respective flanges, and passageways in said heads in alignment with said arbor tube.

15 6. A spool constructed of sheet material and comprising a barrel having flanges at its ends, heads for said barrel secured against the outer sides of said flanges, an intermediate annular portion of each head being deflected inwardly to

20 provide an annular shoulder behind the corner of the respective flange, a brace member extending diametrically across the barrel within each end thereof and welded to the intermediate portion of the respective head, an arbor tube secured at its ends to said brace members, an outwardly extending flange on each brace member concentric with said arbor tube, each head having an axial passageway in alignment with said arbor tube, and an inwardly extending flange on 25 30 each head concentric with and engaged by the flange on the respective brace member.

7. A sheet metal spool comprising a barrel having flanges at its ends, heads for said barrel en-

35 gaging against the outer sides of said flanges and having inward deflections providing shoulders behind the barrel flanges, a brace bar extending diametrically across the barrel within each end thereof and welded to the respective head, inwardly extending flanges on each bar, 40 said heads having axial passageways therethrough and said bars having aligning passageways therethrough, and an arbor tube secured at its ends between the flanges of the respective bars for registration with the passageways through 45 said bars and heads.

8. A sheet metal spool comprising a barrel hav-

50 ing flanges at its ends, heads for said barrel seating against the outer sides of said flanges and being secured thereto and having inward deflec-

55 tions providing shoulders behind the barrel flanges, brace bars extending diametrically across the barrel within the ends thereof and welded to the respective heads and having inwardly ex-

tending flanges forming sockets, and an arbor tube extending axially through said barrel with its ends engaging in said sockets, said heads and bars having axial passageways in alignment with said arbor tube.

HILYARD C. HOWSAM.
